UNITED STATES PATENT OFFICE

157,915

STOPPER OR SIMILAR ARTICLE

Joseph W. Simoneau, Nashua, N. H.

Application December 3, 1948, Serial No. 149,973

Term of patent 14 years

(Cl. D58—10)

To all whom it may concern:

Be it known that I, Joseph W. Simoneau, a citizen of the United States of America, residing at Nashua, in the county of Hillsboro, State of New Hampshire, have invented a new, original, and ornamental Design for a Stopper or Similar Article, of which the following is a specification, reference being had to the accompanying drawings, forming part thereof.

I claim:

The ornamental design for a stopper or similar article, as shown.

JOSEPH W. SIMONEAU.
